TWISTED TOOTH LOCK WASHER

Anthony L. Chiarugi, Bartlett, Ill., assignor to Illinois Tool Works Inc., Chicago, Ill., a corporation of Delaware

Filed Aug. 14, 1961, Ser. No. 131,183

2 Claims. (Cl. 151—35)

The present invention relates to a novel lockwasher and a method and apparatus for producing the same, and more specifically to a novel twisted tooth or prong type lockwasher.

Lockwashers of the type including a plurality of generally radially disposed prongs extending from an annular body section and twisted about their radial axes so as to present locking teeth have long been commercially available. Numerous variations of such washers have been suggested many of which have been considered to be generally satisfactory.

When producing heretofore proposed twisted tooth type lockwashers, one procedure which has been generally followed is to provide a flat washer blank having flat teeth or prongs and then to twist the prongs by engaging them with twisting dies having generally pointed prong engageable teeth. This procedure and such dies have in many instances heretofore been considered to be generally satisfactory. However, in view of the present invention it appears that such heretofore proposed procedures and dies and resulting lockwasher structures resulted in the addition of unnecessary costs to the finished product primarily as a result of a relatively rapid wearing of the dies requiring replacement thereof and the failure to obtain a significant portion of the locking action or holding power available from a given amount of washer stock material.

It is therefore an important object of the present invention to provide a novel lockwasher structure and a novel method and means for producing the same whereby substantial and significant economies in production and material costs may be obtained.

A further important object of the present invention is to provide a novel washer structure having substantially improved locking or holding characteristics.

A more specific object of the present invention is to provide a novel lockwasher of the above described type which is constructed so that increased locking or holding power for a given size washer may be obtained or, if desired, a desired locking or holding power may be obtained with a washer of a given size made from thinner and less expensive stock material.

A still further specific object of the present invention is to provide a novel washer of the twisted tooth or prong type which is constructed so as to provide for greater resistance to collapsing of the teeth and increased tooth edge engagement when the washer is clamped between opposing surfaces of a work structure.

A further specific object of the present invention is to provide a novel die structure for making twisted tooth type lock washers of the above described type, which dies structure is of economical construction and has a useful working life substantially longer than that of certain generally similar die structures heretofore in use.

Other objects and advantages of the present invention will become apparent from the following description and the accompanying drawings wherein:

FIG. 1 is a plan view showing a twisted prong or tooth lockwasher incorporating features of the present invention;

FIG. 2 is an enlarged edge elevational view of a lockwasher incorporating features of the present invention;

FIG. 3 is a sectional view taken generally along line 3—3 in FIG. 2;

2

FIG. 4 is a fragmentary sectional view taken generally along line 4—4 in FIG. 5;

FIG. 5 is a further enlarged fragmentary perspective view showing features of the novel washer structure in greater detail;

FIG. 6 is a view showing the cross sectional configuration of a tooth or prong generally along line 6—6 in FIG. 5.

FIG. 7 is a view showing the cross sectional configuration of the prong generally along line 7—7 in FIG. 5;

FIG. 8 is a perspective view showing a set of dies incorporating features of the present invention;

FIG. 9 is an end view of the lower dies shown in FIG. 8;

FIG. 10 is a sectional view taken along line 10—10 in FIG. 8;

FIG. 11 is a plan view showing a blank from which the lockwasher incorporating features of the present invention may be formed;

FIG. 12 shows the manner in which the dies incorporating features of the present invention engage the teeth or prongs for forming them in accordance with the present invention;

FIG. 13 is a sectional view taken generally along line 13—13 in FIG. 12;

FIG. 14 is a plan view showing a washer incorporating a modified form of the present invention;

FIG. 15 is a plan view showing a washer embodying another modified form of the present invention;

FIGS. 16 and 17 are respectively similar to FIGS. 9 and 10 and show a modified die structure for forming the washer of FIG. 15;

FIG. 18 is an enlarged edge view of the washer shown in FIG. 15;

FIG. 19 is an enlarged fragmentary perspective view of the washer shown in FIG. 15;

FIG. 20 is a view showing the sectional configuration of a washer tooth taken along line 20—20 in FIG. 19;

FIG. 21 is a view showing the sectional configuration of a washer tooth or prong taken along line 21—21 in FIG. 19.

Referring now more specifically to the drawings wherein like parts are designated by the same numerals throughout the various figures, a washer 20 incorporating features of the present invention is shown in FIGS. 1—7, 12 and 13. The washer 20 is formed in the manner which will be described in detail below from sheet material stock such as steel and is provided with an annular body portion 22 having opposite or inner and outer margins 24 and 26. Prongs 28 extend from one of these margins and in this embodiment roots 30 of the prongs are integrally joined to the outer margin 26 of the body portion.

The prongs 28 are preferably substantially uniformly spaced around the body portion 22 and they extend so that their central or longitudinal axes are respectively disposed substantially radially with respect to the annular body section 22. Each of the prongs 28 is twisted and formed in a manner which will be described in detail below so as to locate opposite generally longitudinal or radially extending edges 32 and 34 thereof axially of opposite sides of the body portion 22. Thus, the edges 32 and 34 provide locking teeth engageable with a fastener such as a nut or a screw and a workpiece when the washer is clamped between the fastener and the workpiece.

In accordance with features of the present invention, the washer is provided with pairs of embossed or rib-like areas 36 and 38 associated with each of the prongs 28. The areas or rib like means 36 and 38 of each pair are respectively substantially disposed at opposite sides of the radial axis of their associated prong as shown

best in FIGS. 5-7. Furthermore, these areas are embossed or formed in opposite directions. More specifically, as shown best in FIGS. 6 and 7 each area or rib like means 36 has a cross-sectional configuration with a hollowed or concave surface 40 at one side of the washer and a rounded or convex surface 42 at the opposite side of the washer while each of the areas or rib like means 38 is oppositely formed with a hollowed or concave surface 44 at the same side of the washer as the surface portion 42 of the area 36. The area or rib like means 44 also has a rounded or convex surface 46 at the same side of the washer as the concave surface portion 40 of the area 36.

In FIG. 11 a blank 48 from which a washer 20 is to be formed is shown in a flat condition. In other words, FIG. 11 shows the blank prior to the twisting and forming of the prongs. Thus, this view provides a clearer showing of the fact that in this embodiment the opposite edges 32 and 34 of the prongs converge with respect to each other from relatively broad roots toward relatively narrow terminal free ends of the prongs. With prongs of this structure, the embossed areas or rib means 36 and 38 are preferably formed so that longitudinal center lines thereof diverge with respect to each other from the outer terminal ends of the prongs toward and across the roots of the prongs. As shown best in FIG. 5, the rib means 36 and 38 extend from the outer free terminal ends of the prongs through the roots 30 at the outer margin 26 of the body portion and into the body portion to points 56 and 52 spaced radially inwardly a substantial distance from the outer body portion margin 26 and still spaced radially outwardly from the inner body portion margin 24.

As previously indicated the rib means 36 and 38 associated with each prong are disposed in generally diverging relationship in a direction extending from the outer ends of the prongs inwardly and, more specifically, the rib means 36 and 38 extend generally along their adjacent prong tooth edges 32 and 34. Thus, the radially inner end portion of the rib means 38 associated with each prong is adjacent and converges toward the radially inner end portion of each rib means 36 associated with an adjacent prong as shown best in FIG. 5. The circumferential spacing of the prongs is such that such converging inner end portions of the rib means 36 and 38 of adjacent prongs merge with each other and provide the margin 26 of the washer body portion with an undulated configuration similar to that of a sine wave as shown best in FIG. 4. This undulated outer marginal section of the body presents abutment surfaces 54 and 56 at the high points of their respective rib means 36 and 38 axially of opposite sides of imaginary bounding planes of the flat inner margin 24 of the washer body. The abutment surfaces are engageable with a fastener such as a screw or nut and a workpiece when the washer is clamped between the fastener and the workpiece for providing relatively rigid abutment means for resisting complete collapsing of the prongs.

The rib means 36 and 38 not only provide the aforementioned abutment means surfaces 54 and 56, but by extending along the prongs and particularly in diverging relationship across the junctions between the roots of the prongs and the margin of the washer body portion, the rib means also provide the prongs themselves with a relatively great resistance to collapsing so that the strength and locking power of the washer is materially increased. Furthermore, the roots of the prongs are undulated in the same manner as the outer margin 26 of the body portion so that the edges 32 and 34 of the prongs at the root locations are disposed axially of opposite sides of the body washer for engagement with opposing clamping surfaces of a work structure and a fastener. In other words, substantially the entire lengths of the edges 32 and 34 are presented for engagement with the opposing clamping surfaces so as further to increase the locking

effectiveness of the washer. As indicated above, the inner end portions of the rib means 36 and 38 terminate short of the inner margin 24 of the washer body. Thus, the abutment surface means 54 and 56 gradually decrease in effective height from the outer margin 56. Furthermore, the abutment surface means 54 and 56 are somewhat rounded as they merge into the substantially planar opposite side surfaces of the washer body in the vicinity of the inner margin 24. This structure aids the abutment surface means in resisting collapse under clamping pressures when the washer is secured between a fastener and a work structure.

In accordance with further features of the present invention, die members 58 and 60 are provided for forming the washer 20 from the blank 48. The dies 58 and 60 are substantially identically formed and oppositely disposed when in use, as shown in FIGS. 8, 12 and 13. Thus, each of the die members includes a shank or body portion 62 having a plurality of teeth or ribs 64 formed at one end thereof. As shown best in FIG. 12, each of the ribs 64 has a generally triangular cross-sectional configuration defined by opposite side or flank surfaces 66 and 68. The angles of inclination of the flank surfaces 66 and 68 with respect to a plane perpendicular to the longitudinal axis of the die body 62 are unequal. The flank surface 68 is disposed at an acute angle with respect to said plane approximately equal to the desired angle of twist of the washer prongs while the flank surface 66 is arranged at a larger acute angle with respect to the plane. Thus, the crest 70 of each rib at the junction between the flank surfaces 66 and 68 is offset so as initially to engage a prong during a washer forming operation along a line laterally offset from the radial axis of the prong.

In accordance with features of the present invention, the crests 70 of the ribs or teeth 64 are rounded in cross-section as shown best in FIG. 12. The ribs extend from the peripheral surface of the die body generally toward and substantially to the center of the die body, and the crests 70 progressively decrease in height from the periphery of the body toward the inner ends of the ribs, as shown best in FIG. 13. Roots 72 of the ribs are also inclined with respect to an imaginary plane perpendicular to the longitudinal axis of the die body and, as shown best in FIG. 13, the roots 72 are of maximum depth at the periphery of the die body and progressively decrease in depth toward the inner ends of the ribs. The formation of the ribs or teeth 64 and particularly the inclination of the crests 70 are such as to accomplish twisting of the washer prongs in the manner described above and engagement and forming or embossing of the outer marginal portion of the washer body and without substantial engagement and forming of the inner margin of the washer body.

As shown best in FIG. 9, the ribs 64 are arranged generally radially but at the same time they are arranged so that their crests 70 are not truly on radial lines but are substantially tangent to a small centrally located circular area 74. Preferably, this area 74 is cut away as shown best in FIGS. 9 and 13 so as to facilitate construction of the dies. It is to be noted that when the die member 60 is arranged oppositely from the die 58, the crests 70 of the die member 60 will be inclined with respect to a radial line oppositely from the crests 70 of the die member 58 as can be readily seen by comparing FIGS. 9 and 10. Thus, the ribs or teeth elements of the die members are disposed for forming the rib means or embossed areas at the opposite sides of the washer in the above described relatively diverging relationship.

FIG. 14 shows an internal tooth type lockwasher incorporating features of the present invention. Except for the arrangement of the teeth or prongs internally rather than externally, this washer is constructed in substantially the same manner and includes the same features of the washer 20 described above as indicated by

the application of identical reference numerals with the suffix *a* added to corresponding elements.

FIGS. 15 through 21 show another embodiment of the present invention which is similar to the structure described above as indicated by the application of identical reference numerals with the suffix *b* added to corresponding elements. In this embodiment the ribs or teeth 64*b* of the die members 58*b* and 60*b* extend radially rather than tangentially to a small centrally located circle as shown in FIGS. 16 and 17. This structure further simplifies production of the die members and may result in substantial manufacturing economies.

In this embodiment the rib means or embossed areas 36*b* and 38*b* at opposite sides of the washer teeth or prongs 28*b* are also formed so that they extend substantially radially. As shown best in FIGS. 19 and 21, the radially extending rib means or embossed areas 36*b* and 38*b* terminate short of the free or outer extremities of the prongs so that the extremities are substantially rectangular or flat for aggressively presenting the tooth edges 32*b* and 34*b* thereof.

While the preferred embodiments of the present invention have been shown and described herein, it is obvious that many structural details may be changed without departing from the spirit and scope of the appended claims.

The invention is claimed as follows:

1. A sheet metal lockwasher including an annular body, a plurality of substantially similar circumferentially spaced prongs formed integral with and extending radially from at least one margin of said washer body, each prong being formed by progressive twisting about its generally radial central axis from the root of the prong adjacent said body margin to the free prong extremity so as to present a pair of opposed work engaging and locking margins which normally project axially beyond the opposed bounding planes of said annular washer body, a pair of rib means formed along both of the side locking margins of each prong,

each of said ribs on each prong projecting axially in the direction of twist of their respective locking margin and said ribs on each prong diverging relative to each other from the side margin of the prong positioned radially beyond the margin of the body and extending substantially from the prong extremity to a position radially within at least a portion of the adjacent body margin, said rib overlaying the area of juncture of each locking margin and the margin of said body intermediate the adjacent prong, each of said rib means having in association therewith on the opposed surface of said prong a complementary generally radially arranged indentation of substantially the same area as said rib, the orientation and shape of said rib means and associated indentation being such as to strengthen the prongs to resist untwisting and to cause the margin of the washer body in the vicinity of the prong roots to resist flattening when the washer is clamped between work surfaces.

2. A lockwasher as defined in claim 1, wherein said margin of the body portion to which roots are integrally joined has an undulating configuration and said roots have a corresponding configuration.
